UNITED STATES PATENT OFFICE

EDMUND D. HAM, OF PIKEVILLE, NORTH CAROLINA

RURAL-MAIL-BOX SUPPORT

Application filed December 10, 1929. Serial No. 413,061.

This invention relates to rural mail box supports, and has for its general object the provision of a post including a bracket on which the mail box may be swingably mounted, said mail box being selectively latchable in a forward position in which it faces the road for the convenience of the carrier in delivering mail, and in a position laterally with respect to the road so as to be out of the way of unusual traffic, such as the road scraper, and also bringing the front of the box to a position in which mail can be removed without the necessity of one going outside the gate.

15 A more specific object of the invention is to provide a support for swingably mounting the box, having a positive latch for holding it in mail receiving position, and a detent latch for maintaining it oppositely directed, so that if the carrier finds it in the latter position he can, by taking hold of the box itself readily swing it to its forward position without having to trouble himself by directly manipulating any latch.

20 Still another object of the invention is to provide a post and swinging bracket so co-operably arranged that the bracket is rigidly supported in either of its positions of adjustment, and particularly when in its forwardly extended position.

25 A further object of the invention is to provide for the height adjustment of the mail box support and to construct the support so that it may be shipped, knocked down, in a package of convenient size and be readily assembled without mechanical skill.

Other objects of the invention will appear as the following description of a practical and preferred embodiment of the invention proceeds.

In the drawings in which the same characters of reference are used in the several figures to denote identical parts:

45 Figure 1 is a side elevation of my rural mail box support;

Figure 2 is a plan view taken along the line 2—2 of Figure 1 showing the bracket in forward position;

50 Figure 3 is a section taken along the line

3—3 of Figure 2 showing the bracket in its positive latched position;

Figure 4 is a fragmentary plan view showing the bracket detented by the yielding latch;

55

Figure 5 is a section taken along the line 5—5 of Figure 4.

Referring now in detail to the several figures, numeral 1 represents a post which, for the purpose of the present invention, is of right angular cross section having a front flange 2 and a side flange 3.

A bracket which is in general designated by the reference numeral 4 is mounted adjacent the upper end of the post 1, said bracket preferably comprises an angle iron 5 and a brace 6. Said angle iron provides a flat top flange 7 for receiving the mail box 8 and it also has a side flange to which the brace 6 is secured adjacent one end preferably by pivotal means 65 such as the screw or rivet 9.

The bracket is mounted with its side flange preferably in the plane of the side flange of the post by means of hinges 10 and 11. The hinge 10 is secured to the side flange 5' of the bracket, while the hinge 11 is connected to the lower end of the brace 6. The hinges are preferably of the loose pintle type and are preferably so aligned that a single hinge pintle 12 may be passed through both hinges 75 in assembling the post and bracket.

It will be noted from Figure 2, which shows the bracket in its forward extended position, that the inner end of the top flange 7 abuts squarely against the front flange 2 85 of the post, while the side flange 5', see Figure 3, abuts squarely against the front flange 2 of said post, and furthermore, since the side flange 5' is in the plane of the side flange 3 of the post, any stress exerted downwardly upon the bracket is resisted by the entire width of the side flange of said post. This makes an extremely strong and rigid construction enabling the bracket to be subjected to great abuse without being damaged.

90 The bracket 4 is constructed to be latched in its forwardly extending position by positive means consisting of a latch 13 having a resilient shank 14 secured preferably to the under-side of the top flange 7 and having a 95 100

cam nose 15 adapted to slip automatically over the bottom edge of a notch 16 cut in the upper end of the front flange 2 of the post. The cam nose 15 is provided with a shoulder 17 which when the cam nose has passed across the lower edge of said notch, snaps on the inner side of the front flange rigidly and positively retaining the bracket in its forward position until said latch has been released manually by pressing upwardly upon the cam nose 15 against the tension of the resilient shank 14. Thus, when the support carrying the mail box has been swung to the forward position, it is positively retained in this position until manually released.

It will be noted that the cam nose 15 serves as an operating handle for releasing the latch and that it extends within the angle of the post, being thus protected in a measure from inadvertent release, and the adjacent edge of the side flange of the post serving as a lever for the thumb when the hand is in the act of releasing this latch.

The bracket is adapted to be swung relative to the post through an angle of 180 degrees, that is to say, from a position in which it is directed forwardly toward the road to a position in which it is oppositely directed. In this latter position, one may stand behind the fence or gate and remove the mail without going outside of the gate. Moreover, it is frequently desirable to swing the mail box to this position to avoid its being struck by road implements which may work up close to the post.

A detent latch 18 is provided for normally retaining the bracket in this reverse position, said latch preferably consisting of a resilient member secured to the under-side of the top flange 7 of the bracket and extending freely through an aperture 19 formed in the side flange of the bracket. Said detent latch is formed as shown in Figure 5, with a cam nose 20 and a recess 21 with sloping oppositely disposed cam sides. When the bracket is swung to side-wise position, the cam nose 20 snaps over the lower wall of a notch 22 cut in the side flange of the post, and the detent then snaps down until the lower wall of said notch seats in the recess 21. The cam sides of said recess are such that a pull side-wise on the bracket is sufficient to deflect the detent latch upward and to release the same automatically from its engagement of the post.

It may frequently happen that after taking the mail from the mail box, the bracket 4 is left inadvertently in its reverse position. When the mail carrier arrives subsequently it would be extremely inconvenient for him to place mail in the box in its reversed position, and unreasonable to expect him to take the trouble to manipulate any latch for the purpose of releasing the bracket

so that it could be swung to its forward position. The present detent latch, while holding the bracket normally in reversed position is readily released by the mail carrier by merely taking hold of the mail box and swinging it forwardly.

By having the two latches secured to the lower face of the top flange 7, a flat surface, clear of all mechanism is provided for the reception of the mail box.

In order to enable the mail box to be adjusted at the proper height, the post 1 is preferably made in sections 23 and 24, one section having a plurality of bolt holes 25 capable of being registered with a single bolt hole in the other section. The sections are held together in adjusted position by means such as the bolt and nut indicated at 26 in the drawings.

The rural mail box support embraced in the present invention is constructed with the particular object in view of enabling it to be shipped in knocked down condition in a package of desirable length, and at least short enough to be mailed by parcel post. With this object in view, not only is the post 1 made in sections as described but the hinge pintle 12 may be removed as well as the screws 9 or 27 or both, so that the bracket may be completely separated from the post and the parts arranged into folded position.

The disassembled rural mail box support may be put together without the exercise of any but the most rudimentary mechanical skill, it being only necessary to secure the brace 6 in place, to pass the hinge pintle 12 through both hinges placing a cotter pin 28 in the lower end of the hinge pintle if desired, to prevent its subsequent removal and to adjust the post sections to the desired height.

While I have in the above description, disclosed what I believe to be a preferred and practical embodiment of my invention, it is to be understood that the details of construction as shown, are by way of example only and not limitative in their bearing upon the scope of the invention, which latter is to be determined by the construction of the appended claims.

What I claim is:

1. A rural mail box support comprising a post of angle iron having front and side flanges, a bracket including a box supporting member having top and side flanges, means for swingably mounting said bracket on said post about an axis approximately in the common plane of the side flanges of said post and bracket when the latter is in forward position, the ends of the flanges of said bracket abutting the front flange of said post when said bracket is in said forward position, and a positive latch engageable with said front flange for holding said bracket in forward position.

2. A rural mail box support comprising a post of angle iron having front and side flanges, a bracket including a box supporting member having top and side flanges, means for swingably mounting said bracket on said post about an axis approximately in the common plane of the side flanges of said post and bracket when the latter is in forward position, the ends of the flanges of said bracket abutting the front flange of said post when said bracket is in said forward position, and a positive latch engageable with said front flange for holding said bracket in forward position, the operating element of said positive latch extending within the angle of said post.

3. A rural mail box support comprising a post of angle iron having front and side flanges, a bracket including a box supporting member having top and side flanges, means for swingably mounting said bracket on said post about an axis approximately in the common plane of the side flanges of said post and bracket when the latter is in forward position, the ends of the flanges of said bracket abutting the front flanges of said post when said bracket is in said forward position, and a positive latch engageable with said front flange for holding said bracket in forward position, said bracket being swingable to a position in which its side flange overlies the side flange of said post, and a detent latch projecting laterally from said bracket, engageable with the side flange of said post.

4. A rural mail box support comprising a post, a bracket mounted upon said post swingably about a vertical axis through an angle of substantially 180 degrees to a forward mail receiving position, and to a rearward mail removing position, a positive latch on said bracket for holding the latter in mail receiving position, and a detent yieldable to lateral pressure on said bracket for holding the latter in mail removing position, said post being provided with means with which said latches coact.

In testimony whereof I affix my signature.
EDMUND D. HAM.
